CLAIM

The ornamental design for a work vehicle having ground engaging belt drive apparatus, as shown and described.

DESCRIPTION

FIG. 1 is a right side elevational view of a work vehicle having ground engaging belt drive apparatus showing our new design;

FIG. 2 is a left side elevational view thereof;

FIG. 3 is a front elevational view thereof;

FIG. 4 is a rear elevational view thereof;

FIG. 5 is a top plan view thereof; and

FIG. 6 is a bottom plan view thereof; and

FIG. 7 is a perspective view thereof.
